UNITED STATES PATENT OFFICE.

ALBERT A. FOURNIER, OF OTTAWA, ONTARIO, CANADA.

CUFF-STRETCHING DEVICE.

Application filed May 13, 1925. Serial No. 30,018.

This invention pertains to means for flattening or stretching soft cuffs and holding them in such condition while they are drying.

5 The present invention has for its objects, among others, to provide simple and efficient means readily insertable within a tubular cuff and designed to exert pressure in opposite directions against the opposite 10 edges of the cuff to flatten or stretch the same so that being thus held while drying, the cuff when dried will maintain its flattened condition without the necessity of being ironed.

15 Other objects of the invention is to provide such a device with simple and efficient means serving not only to stretch or flatten the cuff, but to hold the same fixedly in such condition until pressure is relieved.

20 Other objects and advantages of the invention will hereinafter appear and the novel features thereof will be particularly pointed out in the appended claims.

The invention is capable of embodiment 25 in a variety of forms for the accomplishment of the desired end, that herein shown being what I have found to be efficient, but it is to be understood that this is by way of illustration only without any intent of restricting the present invention thereto.

The invention in such preferred form is clearly illustrated in the accompanying drawings, which with the numerals of reference marked thereon form a part of this specification; and in which:—

Fig. 1 is a plan view showing my improvement applied to a cuff, the latter being shown in its flattened condition.

Fig. 2 is an edge view of Figure 1.

Fig. 3 is an enlarged plan view of the device with parts in section.

Fig. 4 is an end view of the same.

Like numerals of reference indicate like parts throughout the several views where they appear.

In carrying out my invention in the form herein shown, I employ two like members 1 and 2, each having at one end a reduced portion as shown at 3, having one face inclined with relation to the straight edge thereof, as seen best in Figure 3, and what may be termed the inner face of this inclined portion is provided with a plurality of notches or the like 4, clearly seen in Figures 1 and 3.

These two members are of a width rela-

tively less than the width of the cuff, but capable of being separated so as to increase the distance between their outer edges, which outer edges are designed to be engaged with the opposite inner edges of the cuff. It is to be understood that the device herein shown and described is adapted for use with what is known as a tubular cuff, that is, a soft cuff having opposite free edges and with the ends open or partially open so that the members 1 and 2 may be readily inserted therein at one end and pushed through so that portions extend beyond the other end of the cuff.

Each of the members 1 and 2 is provided at one end—the end opposite that provided with the notches 4—with a member 5 pivotally mounted thereon as at 6, the other end thereof carrying a lateral projection as at 7, designed to engage in one or the other of the notches 4 of the adjacent end of the opposed member. The members 5 serve, by reason of the engagement of their means 7 which are adapted to engage in the notches 4, to spread or separate the members 1 and 2 and to firmly hold them in such separated condition.

In some instances the members 5 may be composed of two parallel bars or the like 8, as indicated in Figure 2, so as to embrace the members 1 and 2, the function, however, being the same as if the members 5 were each composed of a single piece.

This means of separating and holding the members 1 and 2, while having been found efficient in use, is but one of the various means which I may employ for this purpose and where in the following claims I employ the term: "means to separate said members and hold them in their separated condition", I wish to be understood as covering any substitute for the particular means for this purpose herein disclosed.

The mode of use will be apparent.

The lugs 7 of the members 5 being disengaged from the notches of the adjacent members 1 and 2, the said members 1 and 2 are inserted through the ends of the cuff, one in each direction, as indicated in Figure 1, so as to bring the notched ends of the two members 1 and 2 at opposite ends of the cuff. The members 1 and 2 are made of such relative length that both ends project beyond the ends of the cuff and when having been thus inserted the members 5 are brought into proper posi-

tion so that the members 7 thereof will engage in one or the other of the notches 4 of the inclined members 3, and by changing the relative position of these parts the cuff may be stretched more or less into flattened condition. The pressure exerted on the members 1 and 2 serves to maintain the cuff in such position.

It is to be understood that the cuffs are first washed and rinsed in clear water and the members 1 and 2 then inserted. No starch is necessary, no ironing required, and the cuffs may be placed over a radiator or other source of heat, or allowed to dry over night in the air; the result is a nice clean pair of perfectly laundered cuffs. There is no wear upon the cuffs as in washing and the length of life of the cuff is materially increased.

20 The members 1, 2, and 5 may be made of aluminum, or other rust-proof material, and can be readily stamped out at minimum cost.

Modifications in detail, proportion of parts, etc., may be resorted to without departing from the spirit of the invention or sacrificing any of its advantages.

What I claim as new is:—

1. Means for flattening and stretching a tubular cuff, the same embodying means insertable through the end of a cuff; a provision oppositely disposed at opposite ends of said means for actuating said insertable means to exert outward pressure against opposite edges of the cuff from the inside thereof, and 35 to hold the cuff in flattened condition, said provision embodying means rigid on one of said insertable means.

2. Cuff-stretching means embodying op-

posed cuff-engaging members insertable within a cuff, each having at one end a movably mounted member and at the other end relatively fixed means for adjustable engagement by the said movably mounted member on the adjacent end of the opposed cuff-engaging member.

3. Means insertable within a tubular cuff to hold the same substantially flat while drying, the said means comprising two independently disconnected members insertable within a tubular cuff, and means carried by opposite ends of and oppositely disposed on said members to separate said members after their insertion within the cuff and to hold them in distended condition while the cuff is drying, the means at one end of each member being rigid therewith.

4. Cuff flattening and stretching means embodying two substantially flat members having each at one end pivoted means and at the other end means formed directly 60 therein to be engaged by the pivoted means on the other member after the said members have been inserted within a tubular cuff.

5. A device for the purpose described, 65 consisting of two independent members, each with a plurality of notches at one end formed directly in the member, and a pivoted member at the other end engageable with the notches of the other member, said device being insertable within a tubular cuff to flatten the same, and to hold the same flattened while drying.

In testimony whereof I affix my signature.

ALBERT A. FOURNIER.
